PETRUS KLAAS VAN DER STERR, OF FRANKFORT-ON-THE-MAIN, GERMANY, ASSIGNOR,
BY MESNE ASSIGNMENTS, TO WESTINGHOUSE ELECTRIC & MANUFACTURING COMPANY, A CORPORATION OF PENNSYLVANIA.

RELAY.

Application filed August 29, 1921. Serial No. 496,673.

To all whom it may concern:

Be it known that I, PETRUS KLAAS VAN DER STERR, a subject of the Queen of the Netherlands, residing at Frankfort-on-the-Main, Hanauerlandstrasse 152/158, Germany, have invented certain new and useful Improvements in Relays (for which I have filed applications in Germany Sept. 25, 1917; Aug. 8, 1919; and Jan. 26, 1920), of which the following is a specification.

My invention relates to relays and particularly to relays of the induction type.

The object of my invention is to provide a selective relay for protective purposes that shall be adapted for use in a complicated net-work which requires that certain relays operate before others in case abnormal conditions obtain in the system.

When a short-circuit occurs in a power distribution net-work, it is desirable to have the relays nearest the fault operate first to trip the associated circuit-breakers, in order that the defective feeder or apparatus may be isolated with a minimum disconnection of operative feeders. It has been proposed to accomplish this by the use of relays that depend for their speed of operation upon the voltage existing at the relay, for it will be apparent that the line voltage varies from zero at the short-circuit to the generator voltage at the substation.

In accordance with my invention a relay is provided that is adapted to distinguish between small differences of voltage in order to operate selectively to isolate a defective feeder.

For a better understanding of my invention, reference may be had to the accompanying drawings wherein

Figure 1 is a diagrammatic view of a relay embodying my invention;

Fig. 2 is a side view showing the magnetizable core element and disc of the induction-motor mechanism; and

Figs. 3 and 4 are views of modifications of the relay.

Referring to Fig. 1, the relay comprises a weight 1 adapted to rotate a disc 2 of the induction-motor mechanism in a clock-wise direction. A core element 17 having a voltage winding 3 thereon is disposed adjacent the disc 2. An overload relay 4 is connected in series with the line circuit 18 and controls the operation of the induction-mo-

tor mechanism by means of an electro-magnet 5 having a pivoted armature 6. The armature 6 controls contacts 7 in the circuit of the coil 3 and also operates a detent 8 carried upon the pivoted bar 9.

A shading coil 10 is located upon one of the poles of the core element 17 and is normally short-circuited by the contacts 11. A second shading coil 12 is also arranged upon the core element 17 and is short-circuited, when the relay operates, by the contacts 13. An adjusting resistance 14 is connected in series with the coil 12 to facilitate adjustment of the time of operation of the relay. The coils 3, 10 and 12 are so arranged upon the core element 17 that a counter-clockwise torque is exerted upon the disc 2 when the coil 3 is energized and either of the shading coils is short-circuited.

Upon the occurrence of a short-circuit in the line, the overload relay 4 operates and closes the circuit of the electro-magnet 5. The electro-magnet 5 attracts its armature 6, thereby closing the contacts 7 and removing the detent 8 from engagement with the disc 2, so that the disc is free to rotate. The weight 1 rotates the disc 2 in the clockwise direction. The rate of rotation of the disc 2 depends upon the restraining force produced by the induction-motor torque, since the coils 3 and 12 produce a counter-clockwise torque upon the disc 2. Obviously this torque depends largely upon the current through the coil 3 which depends, in turn, upon the line voltage. During a short-circuit, this is of course dependent upon the distance of the relay from the fault.

Accordingly where several relays are employed at different points in a net-work, the time of operation of each relay depends upon its distance from the fault. Since the voltage is lowest at the short-circuit, the nearest relay will have less restraining torque upon the disc 2 and this disc will be rotated faster than that of any other relay. After the disc is rotated a predetermined distance, the weight 1 strikes the contacts 15, closing the circuit of a trip coil 19, thereby opening the circuit breaker 20 associated with the relay and clearing the fault from the system.

The relay is adapted to reset to normal in case the overload relay 4 opens its contacts either by reason of the fact that the overload

has ceased or that some other relay has operated. Upon the restoration of the armature 6 the contacts 11 are closed and a counter-clockwise torque is produced by the coils 3 and 10. This torque returns the disc 2 to its normal position, winding up the weight 1 until it strikes the stop 21 and unlatches the bar 9. The bar 9 returns to normal and latches the disc 2 in its normal position. The contacts 7 are now opened, thereby stopping the induction-motor mechanism.

In the modification shown in Figs. 3 and 4, the relay is constructed like a reversing relay. When the overload relay 5 operates, it connects the coil 3 with the line circuit through the contacts 7. Thus the operation of the relay depends upon the line voltage. At the same time the relay 5 interrupts the circuit of the coil 10 for producing the resetting torque. After the overload has been relieved, the relay 5 restores and short-circuits the coil 3 and the relay mechanism is reset to normal. As before, 15 designates the tripping contacts of the circuit breaker.

I have found that the sensitivity of selective relays of this type may be increased by using a series resistance of high positive temperature-coefficient. This resistance may be connected as shown at 16 in Fig. 4, so that it is in the circuit of the coil 3 only when the auxiliary relay 5 is operated and closes the contacts 7. By using a series resistance having a high positive temperature-coefficient, the relay becomes sensitive to smaller differences of voltage. In order to obtain the advantage of the temperature-coefficient during the operation of the relay it is necessary to connect it in circuit as shown only during such operation.

I claim:—

1. A relay comprising, in combination, a disc, mechanical means tending to rotate the same in one direction, a voltage responsive coil located in inductive relation to said disc, a second coil inductively related to said voltage coil adapted to produce in conjunction with said voltage coil a shifting magnetic field tending to rotate said disc in the opposite direction, a detent holding said disc in normal position, a switch in the circuit of said voltage coil closed when said detent is released from engagement with said disc, electro-responsive means for releasing said detent, and contacts operated upon a predetermined travel of said disc.

2. A relay comprising, in combination, a metallic non-magnetic member, rotatably mounted, mechanical means tending to rotate said member in one direction, a detent holding said member in normal position,

a voltage responsive coil adapted to be connected across the line circuit located in inductive relation to said member, a second coil inductively related to said voltage responsive coil adapted to produce in conjunction with said voltage responsive coil a shifting magnetic field operating to rotate said member against the action of said mechanical means, means for releasing said detent and connecting said voltage coil across the line, means for holding said detent in released position and the circuit of said voltage responsive coil closed, and means operated by said member to release said latch when said member resumes normal position.

3. In combination, a line circuit, a relay in the line circuit actuated when the current therein exceeds a predetermined value, a circuit breaker for opening the line circuit, a timing mechanism adapted to actuate said circuit breaker after a predetermined movement when released, a detent holding said timing mechanism in normal position, means actuated by said relay when energized to release said detent, motor means for returning said timing mechanism to normal position, and means operated by said timing mechanism upon reaching normal position to operate said detent.

4. A relay comprising, in combination, an induction motor mechanism adapted to open the line circuit after a predetermined movement from normal position, means for setting said timing mechanism in operation controlled by the current in the line, and means for resetting said mechanism to normal, said last-named means also governing the rate of movement of said mechanism in accordance with the voltage of the line at the point where said relay is located.

5. A relay comprising contacts, a rotatable disc having a normal position, a detent for said disc, mechanical means for rotating said disc in one direction to operate said contacts, means for resetting the disc to normal comprising a magnetizable core member having windings thereon, and means including one of said windings for producing a restraining torque during the operation of said relay.

6. A relay comprising contacts, a rotatable disc for actuating the same, mechanical means for driving the disc to operate said contacts, and means including a magnetizable core member having a winding thereon for restraining the contact-operating movement of said disc and for resetting the disc to normal.

In testimony whereof I affix my signature.

PETRUS KLAAS VAN DER STERR.
